UNITED STATES PATENT OFFICE.

LOUIS STEINBERGER, OF BROOKLYN, NEW YORK.

DESIGN FOR A COMBINED DIAL AND KNOB.

Application filed July 1, 1922. Serial No. 2,918. Term of patent 14 years.

To all whom it may concern:

Be it known that I, LOUIS STEINBERGER, a citizen of the United States, and a resident of the borough of Brooklyn, city, county, and State of New York, have invented a new, original, and ornamental Design for Combined Dial and Knob, of which the following is a specification.

The design is illustrated in the accompany drawing in which Fig. 1 is a side ele-

vation showing my new design, Fig. 2 is a plan view and Fig. 3 is a perspective view thereof.

I claim:

The ornamental design for a combined dial and knob, as shown.

In witness whereof I have hereunto set my hand at the city, county, and State of New York, this 29 day of June, 1922.

LOUIS STEINBERGER.
